(57) **CLAIM**

The ornamental design for a water sprinkler, as shown and described.

DESCRIPTION

FIG. 1 is a top view of a water sprinkler.

FIG. 2 is a bottom view of the water sprinkler shown in FIG. 1.

FIG. 3 is a front view of the water sprinkler shown in FIG. 1 (i.e., as seen from a right side of the view shown in FIG. 1).

FIG. 4 is a left side view of the water sprinkler in FIG. 1 (i.e., as seen from a bottom side of the view shown in FIG. 1).

FIG. 5 is a right side view of the water sprinkler in FIG. 1 (i.e., as seen from a top side of the view shown in FIG. 1).

FIG. 6 is a top-front-left perspective view of the water sprinkler shown in FIG. 1; and,

FIG. 7 is a top-front-right perspective view of the water sprinkler shown in FIG. 1.

The broken lines shown in FIGS. 1-7 illustrate environmental structure that forms no part of the claimed design.

1 Claim, 6 Drawing Sheets
